UNITED STATES PATENT OFFICE.

JOSEPH L. DONAT, OF CHICAGO, ILLINOIS.

SPARK-PLUG.

1,290,121.

Specification of Letters Patent.

Patented Jan. 7, 1919.

Application filed June 14, 1917. Serial No. 174,651.

To all whom it may concern:

Be it known that I, JOSEPH L. DONAT, a citizen of the United States, residing at Chicago, in the county of Cook and State of Illinois, have invented certain new and useful Improvements in Spark-Plugs, of which the following is a specification.

My invention relates to improvements in spark plugs.

10 The primary object of my invention is to provide a spark plug which will produce a magnetic field at the terminal end of the central conductor, whereby to enlarge and push out, or project the spark, to produce a larger, stronger and more enduring charge, igniting flame with a given current.

Another object of my invention is to reinforce and strengthen the relatively refractory insulating body of the structure, such 20 as porcelain, or the like, by embedding more or less of the central conductor therein, by molding the porcelain around it.

Another object of my invention is to provide means, in the central conductor, such 25 as a spiral portion thereof, whereby the proximity of the sparking electrodes may be varied by elongating or contracting the spiral.

Other, further and more specific objects 30 of my invention will be readily understood, by persons skilled in the art, from a consideration of the following description when taken in conjunction with the drawings, wherein:—

35 Figure 1 is a central vertical section of my preferred form of spark plug.

Fig. 2 is a similar view of a modification.

Fig. 3 is a cross section, taken on line 3—3 of Fig. 1.

40 In all the views the same reference characters are employed to indicate similar parts.

In the embodiment illustrated in the accompanying drawings, 5 is a plug body, threaded as at 6, for insertion in the cylinder head of an engine. 7 is an insulating body of porcelain, or the like, provided with a shoulder 8, for insertion in the larger upper portion of the plug body, and 9 is a more or less, yieldable washer, upon which the enlarged portion 8 of the porcelain structure is seated and 10 is a similar washer under the screw threaded bushing 11. Between these washers the porcelain body 7 is held in place, as usual in such structures.

55 The central conductor, of the plug 12, is

preferably spiral in form, terminating in an enlarged, axially extending threaded part 13 for the wire clamping nut 14. The helical portion of the central conductor terminates in an axially extending terminal 15, 60 for coöperation with the terminal or electrode 16 that is connected to the body part of the plug 5. Between the terminals 15 and 16 the spark is produced.

The modified form shown in Fig. 2 contains substantially the same parts in the same relations and which are indicated with the same reference characters with addition of the exponent prime (') but in this form of the structure the spiral 17 of the central conductor 12, extends to a shoulder 18 formed by conjunction of the two coaxial perforations in the porcelain body part 7'. The axially extending enlarged threaded stem 13 is somewhat longer than the one 70 shown in Fig. 1 and passes freely through an axially extending perforation 20 made in the porcelain body 7'. A concentric but larger perforation 21 is made in the lower portion of the porcelain, to accommodate the 75 spiral 17. In Fig. 2 the central conductor may be bodily removed from the porcelain body 7' by disengaging and removing the holding nut 23' and the wire clamping nut 14'. 85

The electric current passing through the central conductor will pass over the lower portion thereof in spiral form, producing a magnetic field in the neighborhood of the terminals 15 and 16, thereby causing the 90 spark to be projected from the electrodes 15 and 16 in a superficially larger or more extensive body, thereby providing a greater igniting surface for the explosive charge, and extending farther into the charge, as the result of its magnetic projection. There is 95 more or less self induction produced by the spiral of the central conductor, which has the effect to prolong the duration of the spark, to some extent, thereby increasing the 100 efficiency of the plug structure.

The central conductor 12' of the structure shown in Fig. 2 may be bodily removed and another structure of similar character placed in its stead. In Fig. 1, however, the 105 central conductor 12 is immovably associated with the surrounding porcelain insulating body 7.

While I have herein shown and described a single embodiment of my invention, with 110

one modification, it is manifest that other modifications may be made, within the scope of the appended claim.

Having described my invention, what I claim is:—

A spark plug comprising an insulating body having an axial bore of two diameters, the larger bore being in the lower end of said body; a shoulder formed by the con-
10 junction of said bores; a central conductor,

comprising a larger, straight portion for inclusion in the smaller bore and a spirally wound portion, of smaller diameter, for inclusion in the larger bore, the free terminal end of the spiral forming one electrode of the spark gap and a shell having a coöperating electrode.

In testimony whereof I hereunto set my hand.

JOSEPH L. DONAT.
